CLAIM

The ornamental design for an electronic vaping device, as shown and described.

DESCRIPTION

FIG. 1 is a front perspective view of an electronic vaping device;

FIG. 2 is a rear perspective view of the electronic vaping device of FIG. 1;

FIG. 3 is a front elevation view of the electronic vaping device of FIG. 1;

FIG. 4 is a rear elevation view of the electronic vaping device of FIG. 1;

FIG. 5 is a left side elevation view of the electronic vaping device of FIG. 1;

FIG. 6 is a right side elevation view of the electronic vaping device of FIG. 1;

FIG. 7 is a top plan view of the electronic vaping device of FIG. 1; and,

FIG. 8 is a bottom plan view of the electronic vaping device of FIG. 1.

The portions of the design shown in broken lines form no part of the claimed design.

1 Claim, 5 Drawing Sheets

Related U.S. Application Data

continuation-in-part of application No. 14/998,020, filed on Apr. 22, 2015, now Pat. No. 10,064,432.
